W. Taylor Company, Warren, Ohio, a corpora-
tion of Ohio

Application July 30, 1932, Serial No. 626,281

6 Claims. (Cl. 137—160)

My invention relates to mufflers for silencing the exhaust noise of internal combustion engines and other engines periodically discharging expanding and noise producing pulsating gases.

5 The general object of my invention is to provide a short compact muffler having a very high degree of silencing or muffling efficiency combined with a relatively low back pressure.

10 A further object of my invention is to provide a short compact muffler capable of efficient scavenging action with reversed flow of the exhaust gases.

15 A still further object of my invention is to provide a short compact muffler with reversed flow of the exhaust gases in which the exhaust gas streams may readily expand and in which oppositely travelling pulsating exhaust gas streams may partly merge and thus level their peaks.

20 Other and further objects of my invention pertaining to the novel features of construction, combination and arrangements of parts are hereinafter more fully set forth, pointed out in the claims and shown in the accompanying drawings in which:

Figure 1 is a longitudinal sectional view through a muffler embodying the invention, the section being taken on line 1—1 of Figure 2;

25 Figure 2 is a cross sectional view of the muffler shown in Figure 1, the section being taken on line 2—2 of Figure 1;

30 Figure 3 is a perspective view of the pipe supporting skeleton including the solid separating wall between the inlet and outlet pipes of the muffler;

Figure 4 is a longitudinal sectional view through a modification of the muffler shown in Figures 1 through 3;

35 Figure 5 is a sectional view on line 5—5 of Figure 4;

Figure 6 is a longitudinal sectional view through another modification of the muffler and Figures 7 and 8 are sectional views on line 7—7 and 8—8 respectively of Figure 6;

40 Figure 9 is a longitudinal sectional view through still another modification of the muffler;

Figure 10 is a sectional view on line 10—10 of Figure 9; and

50 Figure 11 is a perspective view of the pipe supporting skeleton of the muffler shown in Figures 9 and 10 having a partly perforated separating wall between the pipes of the muffler arranged in the compartment formed by said separating wall.

55 In the form of muffler for internal combustion engines shown in Figures 1 through 3 of the drawings, an outer preferably cylindrical sheet metal shell 1 is closed at its opposite ends by

partition walls 3, slightly spaced from end walls 2 form narrow spaces 4 at the ends of the cylinder which spaces are filled with foraminous sound absorbing material 5, such as expanded mica, slag wool, steel wool and the like. These packed sound absorbing spaces are not absolutely necessary to the proper functioning of the muffler, and therefore may in most instances be eliminated.

5 Mounted within the shell 1 are a series of parallel perforated tubes 6, 7 and 8 through which exhaust gas passes in the order named. Apertured annular sheet metal disks 9 snugly fitted within and adjacent each end of cylinder or shell 1 serve as supports for tubes 6, 7 and 8 and also form chambers 10 and 11, between said disks and partition walls 3 for communication of tubes 6 and 7 and tubes 7 and 8 respectively to induce reversal of the flow of exhaust gas when passing from one tube into the other. The tube 6, the intake tube, extends with its intake end through end wall 2 at the intake end of shell 1 for connection with the engine exhaust, not shown, and at its other end into chamber 10 communicating with pipe 7. The tube 8 communicates at its inner end with chamber 11 and exhausts through end wall 2 at the exhaust end of shell 1. The tube 7 is solely supported by the apertured disks 9 and

20 communicates at opposite ends with the respective chambers 10 and 11. Disks 9 are preferably made from imperforate metal except where provided with apertures for tubes 6, 7 and 8. A longitudinally extending separating wall 12 arranged between the inner wall of shell 1 and tube 7, divides the latter into two longitudinal compartments 14 and 15, each of which accommodates one of the tubes 6 and 8. These compartments are packed with sound absorbing material such as used in the spaces 4, which

25 material occupies the space around the perforated tubes and completely fills each compartment. The separating wall 12 is welded or otherwise secured at its ends to the disks 9 and at its longitudinal edges to the inner face or wall of the shell 1 and to the outer face or wall of perforated tube 7. Preferably the separating wall 12 is of solid sheet metal for reasons

30 which will be presently explained. That portion of the tube 6 which passes through chamber 11 at the inlet end of shell 1, as well as that part of tube 8 which passes through chamber 10 at the exhaust end of the shell 1 are solid, that is the perforations formed in the remainder of these tubes are omitted.

35 Exhaust gases entering tube 6 flow therethrough into chamber 10 thence back through tube 7 into chamber 11 and finally into and through tube 8 to the open atmosphere. This flow takes place because the solid wall 12 sepa-

rates the tubes 6 and 8, in which the flow of gas is in the same direction. The tube 7 in which the flow of gas is in opposite direction communicates with tubes 6 and 8 through the 5 perforations of all tubes and the sound absorbing material occupying the space around the perforated tubes.

It is understood that compartments 14 and 15 communicate with each other through perforated tube 7 and that the perforated tubes 6 and 8 arranged in said compartments communicate indirectly with each other. This is a most important feature of my invention. If the employment of solid wall 12 would not permit such 10 communication, it would be necessary to make the diameter of the cylinder or shell 1 much larger in order to make compartments 14 and 15 large enough for the efficient absorption of sound in the sound absorbing material packed 15 therein. However, by virtue of the perforated tube 7, which serves as an elongation of the separating wall 12 separating the inner chamber of shell 1 into compartments 14 and 15, the impulses in the gas stream passing through 20 tubes 6, 7 and 8 are not confined to the compartment housing each particular tube, but are free to expand through the perforated tube 7 directly into the other housing and its perforated tube in which the flow of gas is in the same direction. Thus impulses in the stream of 25 exhaust gases flowing through tubes 6 and 8 in the same direction, that is from the front to the rear of the muffler, are not free to merge directly with each other, but only indirectly 30 through tube 7, whereas the impulses in the stream of gases flowing through tube 7 in a direction opposite to that of the flow through tubes 6 and 8 are free to merge with the latter 35 and vice versa. This makes it possible for the high impulses in the gas streams in tubes 6 and 40 8 to expand through the perforations of their tubes and merge with the low impulses of the gas stream in perforated tube 7, and this merging of the high and low impulses is continuously 45 taking place throughout the entire muffler. As the gas streams in tubes 7 and tubes 6, 8 are flowing in opposite directions the merging action is greatly multiplied and consequently an extremely high degree of muffling efficiency is attained in spite of the fact that the muffler is of very short length. As the direction of flow 50 of gases passing through tubes 6 and 8 is the same in each of said tubes, and the shearing or merging action previously referred to can not take place under such conditions, separating 55 wall 12 is made solid to separate these tubes from each other. If wall 12 should be perforated, then the merging efficiency between tubes 6 and 8 would be no greater than that of a conventional straight stream acoustic muffler, because the muffling effect attained in the short muffler would be insufficient to prevent noise produced by the short cut, part of the gases would take from tube 6 to tube 8.

The acoustic material between disks 3 and end walls 2 has a material effect on muffling efficiency and acts favorably upon the gas stream as it expands into chambers 10 and 11. However, as previously stated, the disks 3 and the packing between these disks and the end walls 2 may be omitted without any noticeable effect with many engines now on the market, particularly with eight or twelve cylinder engines. The 70 action on the gases previously described, that is the expansion of the exhaust gas stream peaks 75

from one tube through the sound absorbing material into the low pressure area of the exhaust gas stream of another tube and vice versa, provides the necessary expansion for efficient muffling in a muffler in which the chambers are much smaller than the required size of such chambers for conventional acoustic mufflers. The described action of the gases also reduces the back pressure of the muffler. Experiments with reverse stream mufflers not provided with 10 seeping passages between their individual gas channels show a very material increase in back pressure, as compared to that of straight stream mufflers of the same capacity. This is due to the fact that the entire stream is twice completely reversed in the former structure. In my present invention I provide for a progressive transfer of exhaust gases from one compartment to the other compartment, which transfer takes place through a tube in which the exhaust gas stream travels in opposite direction as compared with the direction of travel of gas in the tube from which the peaks of the gas stream are expanded. This transfer action more than compensates for the increase in back pressure set up by the two reverses of the gas stream. 15 20 25

The progressive transfer or merging of impulses also results in a highly efficient scavenging action, as the gases are not trapped in the muffler, but are constantly passing along the inner shell from one chamber to the other so that the entire muffler becomes hot and is maintained at a temperature above the condensation of water and other liquids present in the 30 exhaust gas, even in extremely cold weather and under conditions of intermittent and slow driving. 35

The modified form of the invention shown in Figures 4 and 5 of the drawings functions in 40 substantially the same manner as the preferred form just described. In this modification the tube 7' is slightly spaced from the inner wall of the shell 1 and the separating wall 12' abuts against the outer wall of said tube 7'. This arrangement permits seeping of expanded gas impulses through the elongated passage 16 between the inner wall of shell 1 and tube 7'. A material increase in the size of this passage by spacing tube 7' a greater distance from the inner wall of shell 1 would decrease the silencing 45 action of the muffler because a substantial volume of insufficiently merged and muffled gas will enter into tube 8 and thence be exhausted with substantial noise. Space 16 should be held to a size which insures sufficient merging between expanded gas peaks from tube 7' with the gas creeping and passing through said space 16. 50 55

In the modified form of the invention shown in Figures 6, 7, and 8 which is generally the 60 same as the preferred form of the invention shown in Figures 1 through 3 the perforations of tube 7'' extend only half circumferentially around the said tube 7'' and at opposite ends of said tube are approximately 180° offset with 65 respect to each other. Consequently one half of the length of the tube is perforated for communication with chamber 14 and the other half of the tube is perforated for communication with chamber 15, see Figures 7 and 8. This arrangement decreases the merging action of the exhaust streams in tubes 7'' and 6 but prevents direct expansion of peaks of the exhaust gas stream from tubes 6 into tube 8. Such muffler 70 possesses high muffling efficiency for extremely 75

short structures but shows a slight increase in back pressure as compared with the very low back pressure of the previously described structures.

5 The modified form of the invention shown in Figures 9 and 11 shows a muffler with a non-perforated intake tube 18 displacing tubes 7 and 7" of the structures shown in the previous figures. The tubes 19 and 20 of the modified form are 10 perforated and arranged in compartments 14' and 15' separated from each other by a separating wall 12' similar to the arrangement of wall 12 previously described, with the exception that wall 12' is perforated throughout approximately 15 half its length. The direction of the exhaust gas in tubes 19 and 20 being opposite, the partly perforated separating wall 12', is provided to permit expansion of the peaks of the exhaust gas stream and merging of these streams with 20 satisfactory muffling action, but the back pressure of this structure is slightly increased as compared with the very low back pressure of the structures shown in Figures 1 through 5.

Having thus described my invention, what I 25 claim is:

1. In a reverse stream muffler for silencing the exhaust noise of internal combustion engines, a shell provided with intake and outlet openings and longitudinally subdivided into parallel 30 compartments, foraminous sound absorbing material in said compartments, a gas passage in each of said compartments, one of said gas passages being in communication with said intake opening and another in communication with 35 said outlet opening, and a gas passage arranged parallel to, intermediate of and partly within each of said compartments and in direct communication with said other gas passages to provide a single continuous passage through the 40 muffler and the walls of said passages being foraminous to permit seepage of exhaust gas from these passages into said compartments and back into said passages.

2. In a reverse stream muffler for silencing the 45 exhaust noise of internal combustion engines, a shell longitudinally subdivided into two parallel compartments, foraminous sound absorbing material in said compartments, a perforated tube in each of said compartments, a tubular extension for one end of each of said perforated tubes, said tubular extensions being extended through the opposite end walls of said shell to provide 50 intake and outlet passages for said muffler, and a third perforated tube arranged parallel to, intermediate of and partly within each of said compartments for indirect communication with said compartments and their respective perforated tubes, said third perforated tube directly 55 communicating at opposite ends with said two perforated tubes to provide a continuous unrestricted and reversed gas passage through said shell.

3. In a reverse stream muffler for silencing the 60 exhaust noise of internal combustion engines, a shell provided with intake and outlet passages and longitudinally subdivided into two parallel compartments, longitudinally communicating through a narrow space with each other, foraminous material within said compartments, 65 a perforated tube longitudinally extending in each of said compartments, one of said perforated tubes communicating with said intake passage and the other one with said outlet passage, and a third perforated tube arranged 70 parallel to and intermediate said two compartments.

ments for communication with each of said compartments and their respective gas passages, said third perforated tube being in direct communication with said other perforated tubes to provide a single reversed and unrestricted 75 passage through said muffler.

4. In a reverse stream muffler for silencing the 80 exhaust noise of internal combustion engines, a shell provided with intake and outlet passages and longitudinally subdivided into parallel compartments by a solid wall, a perforated tube supported upon the upper edge of said wall and contacting with the inner wall of said shell, to 85 permit communication of said compartments with each other through said tube, a perforated tube longitudinally arranged in each of said compartments and sound absorbing and deadening material packed within said compartments and enclosing said tubes, one of said last mentioned tubes being in direct communication with the intake passage and the other of said last-mentioned tubes being in direct communication with said outlet passage, said tubes being in direct communication with said first-mentioned perforated tube to provide an unobstructed 90 reversed single gas passage through said shell and permitting expansion of the peaks of explosion impulses into said compartments and the tubes therein.

5. In a reverse stream muffler for silencing 95 the exhaust noise of internal combustion engines, a shell provided with intake and outlet openings and longitudinally subdivided into two parallel compartments, foraminous sound absorbing material in said compartments, a gas 100 passage in each of said compartments, one of said gas passages being in communication with said intake opening and the other one in communication with said outlet opening and a gas 105 passage arranged parallel to, intermediate of and partly within each of said two compartments, the walls of said passages being foraminous for affording communication between each 110 of said compartments and its gas passage, said latter gas passage being in direct communication with said other two gas passages to provide a single continuous and reversed gas passage 115 through the muffler and the foraminous walls of said passages permitting seeping of exhaust 120 gas from these passages into said compartments.

6. In a reverse stream muffler for silencing the 125 exhaust noise of internal combustion engines, a shell provided with intake and outlet passages and longitudinally subdivided into parallel compartments by a partly perforated wall, a tube 130 supported upon the upper edge of said wall and contacting with the inner wall of said shell, a perforated tube longitudinally arranged in each of said compartments and sound deadening material packed within said compartments and enclosing said perforated tubes therein, said tube 135 supported in said wall being in direct communication with said inlet passage and one of said perforated tubes, the other one of said perforated tubes being in direct communication with said last perforated tube and said outlet 140 passage to provide a single gas passage through said muffler having the exhaust gas stream flowing through said perforated tubes in opposite 145 directions and permitting expansion of the peaks of explosion impulses from one of said perforated tubes into its compartment and thence through said perforated wall into the other compartment and its perforated tube.

PAUL G. PEIK. 75
